UNITED STATES PATENT OFFICE.

ROBERT RAYMOND CAREY, OF PHILLIPSBURG, NEW JERSEY, AND WILLIAM L. LUKENS AND LEIGHTON N. D. MIXSELL, OF BETHLEHEM, PENNSYLVANIA, ASSIGNEES TO BETHLEHEM STEEL COMPANY, OF BETHLEHEM, PENNSYLVANIA, A CORPORATION OF PENNSYLVANIA.

PERCUSSION-FUSE.

1,397,855.

Specification of Letters Patent.

Patented Nov. 22, 1921.

Application filed August 19, 1918. Serial No. 250,566.

To all whom it may concern:

Be it known that we, ROBERT R. CAREY, WILLIAM L. LUKENS, and LEIGHTON N. D. MIXSELL, all citizens of the United States, and residing, respectively, at Phillipsburg, Warren county, New Jersey, Bethlehem, Lehigh county, and Bethlehem, Northampton county, Pennsylvania, have invented certain new and useful Improvements in Percussion-Fuses, of which the following is a specification.

This invention relates to improvements in fuses for explosive projectiles, and more particularly that type of fuse in which the firing pin is normally prevented from striking the primer by locking means which can only be withdrawn by centrifugal action. In the present instance the firing pin point is surrounded by a guard which prevents it from approaching near enough to the primer to contact with the latter, the guard being retained in this position by the centrifugally operated locking means. The invention will be particularly described in connection with the accompanying drawing, in which:—

Figure 1 is a longitudinal view through a base fuse showing the parts in normal or inactive position;

Fig. 2 is a similar view showing the relation of the parts after the projectile has been fired and at the moment of impact;

Fig. 3 is a section on the line A—A of Fig. 1; and

Fig. 4 is a section on the line B—B of Fig. 1.

Fig. 5 is a sectional view of a slightly modified form.

Referring to the drawing, 10 indicates the body of the fuse which is adapted to fit in a central threaded opening in the base of the projectile. The fuse body has a central cylindrical cavity 11 in its forward end and threaded into the forward end of this cavity is a container 12 which holds a charge 13 of explosive composition for igniting the main bursting charge of the projectile. In the rear of the container 12 is a primer seat 14 which is clamped against a shoulder 15 by the container, while suitably located, centrally, in the primer seat is a primer 16, which is separated from the explosive composition by a thin disk of suitable material. The construction described provides a cy-

lindrical cavity 11 for the firing pin and its associated parts. These parts comprise a 55 cylindrical hammer body 20 on which is fixed an axially arranged firing pin 21, the point of which extends forward of the body. Surrounding the firing pin at its forward end is a cylindrical guard 22 which is normally located in its forward position with its front end surface flush with or forward of the firing pin point and held in this position by centrifugal bolts 23 which are normally pressed into contact with the firing 65 pin by springs 24. When these bolts are in the position shown in Fig. 1 they prevent rearward movement of the guard 22. The bolts 23 operate in radial openings in the hammer body and the guard 22 is free to 70 move rearwardly in an axial opening in the hammer body when the bolts are withdrawn. The guard is provided with an annular flange 25 which limits forward and rearward movement. A thin metal sheath 26 75 surrounds the hammer and forms an abutment for the springs 24. The sheath has a circular opening through which the forward end of the guard normally projects and the margin of which engages the flange 25. The 80 sheath is placed over the hammer after the parts are assembled and retained in position by any suitable means, such as by spinning its rear edge over the margin of the base of the hammer, as shown.

The hammer is normally held at the rear of the cavity 11 by a spring 27. If it should accidentally move forward before the projectile is fired the guard will come in contact with the primer seat and prevent contact of the firing pin with the primer. When the projectile is fired the locking bolts 23 move radially outward and assume the position shown in Fig. 2 during the flight of the projectile. When the projectile is suddenly retarded, as by striking an object, the hammer moves forward to the position shown in Fig. 2. The guard being free to move rearward, it permits the firing pin point to strike and fire the primer, which ruptures the dia- 95 phragm 17 and ignites the explosive compo- 100 sition 13 which, in turn, ignites the bursting charge of the projectile.

The construction described constitutes a very simple, compact and safe fuse which 105 is certain in operation when fired. The

primer seat 15 is preferably provided with a heavy boss 15^a surrounding the primer and sufficiently strong to prevent injury to the primer by any accidental forward movement 5 of the hammer before firing.

In the form shown in Fig. 5 the guard 22^a has an annular recess in which is located a spring 29^a which has the function of the spring 27, Fig. 1. To hold the hammer body 10 normally at the rear of the cavity, the guard 22^a is preferably elongated so that, in its normal position, it is nearly or quite in contact with the primer seat. As soon as the bolts 23 have been withdrawn from the rear 15 of the guard, the guard is free to move rearward relatively to the hammer body, permitting the firing pin to strike the primer. In other respects the construction shown in Fig. 5 is like that shown in Figs. 1 to 4 inclusive.

Having thus described our invention what we claim as new and desire to secure by Letters Patent is:

1. In a fuse for projectiles, a hammer 25 comprising a cylindrical body, a centrally arranged firing pin fixed to the body and an annular guard surrounding the forward end of the firing pin and movable in a cavity in the hammer body to protect or 30 expose the point of the pin, in combination with a bolt operating in a radial opening in the hammer body and normally arranged in the rear of the guard to hold it in protecting position, a fixed closure movable with 35 said body for the outer end of said opening, said bolt being movable under the influence of centrifugal force to free the guard and permit it to expose the point of the pin.

2. In a fuse a firing device comprising a 40 cylindrical hammer body having an axially arranged firing pin, and having an axial opening surrounding the firing pin, an annular guard in said opening and surrounding the firing pin, radially acting bolts arranged in radial cavities in rear of the guard cavity, and a casing surrounding and secured to the hammer body and closing the outer ends of the bolt cavities, the forward 45 end of the casing being turned inwardly across the guard cavity and adapted to limit the forward movement of the guard.

3. In a fuse structure the combination 50 with a fuse body having a cylindrical cavity therein, of a primer seat carrying a centrally arranged primer closing the forward end of the cavity, a movable member in said cavity having an outer cylindrical surface loosely fitting the inner surface of said cavity comprising, a hammer body constituting a part of said movable member carrying a centrally arranged firing pin and provided 55 with a bore or opening in its forward end surrounding said pin, a movable guard with a central bearing surface loosely surrounding said pin and fitting partly within said

bore and longitudinally movable within fixed limits, coöperating means on said guard and member within said bore limiting the forward movement of said guard to a position around and protecting the point 70 of said pin and centrifugally releasable locking means within said movable member for normally holding said guard in its forward protecting position.

4. As an article of manufacture a firing 75 device adapted for use in the cylindrical cavity of a fuse body having an outer cylindrical surface adapted to loosely fit in said cavity and to move longitudinally therein, comprising a cylindrical hammer body having a central opening or bore in one end, a firing pin secured to said body centrally of said bore and projecting at its forward end beyond the forward end of said body, a guard surrounding said pin and freely movable thereon between fixed limits within said bore, and adapted to project therefrom around the point of the pin and automatic centrifugally releasable means around said pin at the inner end of said guard inclosed 85 within said member to hold said guard in its forward position.

5. An article of manufacture of the class described comprising a hammer body having an outer surface cylindrical in form and 95 provided with a centrally arranged cavity extending longitudinally from the forward end toward the rear end and with radial openings at the rear end of said cavity, a firing pin extending centrally from the bottom of said cavity to a point beyond the forward end of said hammer body, a guard surrounding and freely movable on said pin longitudinally in said cavity with its forward end normally at least as far forward as 100 the tip end of said pin, coöperating peripheral abutments on said guard and on said hammer member within said cavity to limit the forward movement of said guard, spring pressed bolts in said radial openings bearing 110 against said pin behind the inner end of said guard and normally holding it in its foremost position.

6. An article of manufacture of the class 115 described comprising a hammer body having an outer surface cylindrical in form and provided with a centrally arranged cavity extending longitudinally from the forward end toward the rear end and with radial openings at the rear end of said cavity, a firing pin extending centrally from the bottom 120 of said cavity to a point beyond the forward end of said hammer body, a guard surrounding and freely movable on said pin longitudinally in said cavity with its forward 125 end normally at least as far forward as the tip end of said pin, spring pressed bolts in said radial openings bearing against said pin behind the inner end of said guard and normally holding it in its forward position, 130

a thin sheet metal cylindrical casing secured on the outer surface of said hammer body closing the outer ends of said radial openings and having its forward end bent inwardly over the end of said hammer body and partly across the cavity therein forming an abutment flange and a peripheral flange on said guard behind said inturned end to coöperate therewith and limit the forward movement of said guard.

7. A self contained hammer body for fuses comprising a smooth outer continuous and imperforate cylindrical surface, a central pin in a central cavity in an end of said

body and projecting therefrom a guard in 15 said cavity normally with its forward end projecting from said hammer body surrounding and protecting the point of said pin but freely movable on said pin to the rear and centrifugally releasable means 20 wholly inclosed in said body for normally holding said guard in its forward protecting position.

In testimony whereof we affix our signatures.
